UNITED STATES PATENT OFFICE.

YUSKE MIYASAKI, OF MCKEES ROCKS, PENNSYLVANIA.

LOCKING MECHANISM.

1,365,843.

Specification of Letters Patent. Patented Jan. 18, 1921.

Application filed April 14, 1920. Serial No. 373,874.

To all whom it may concern:

Be it known that I, YUSKE MIYASAKI, a subject of Japan, residing at McKees Rocks, in the county of Allegheny and State of Pennsylvania, have invented certain new and useful Improvements in Locking Mechanism, of which the following is a specification, reference being had to the accompanying drawings.

10 This invention relates to certain improvements in lock mechanism and has relation more particularly to a mechanism especially designed and adapted for use in connection with the actuating rods or shifter rods embodied in the transmission of a motor driven vehicle, or the like, and it is an object of the invention to provide a novel and improved mechanism of this general character which operates to hold the actuating rods 15 or shifter shafts, when in neutral position against movement to prevent unauthorized use of the vehicle or the like.

It is another object of the invention to provide a novel and improved mechanism of 25 this general character which is key actuated to either engage or disengage the actuator rods or shifter shafts.

An additional object of the invention is to provide a novel and improved device of 30 this general character comprising two members one movable toward or from the other and which movement is accomplished by the rotation of the second member and wherein the first named member is provided with 35 means to hold the actuator rods or shifter shafts against movement when said rods or shifter shafts are in neutral position.

The invention consists in the details of construction and in the combination and arrangement of the several parts of my improved mechanism whereby certain important advantages are attained and the device rendered simpler, less expensive and otherwise more convenient and advantageous 45 for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a vertical sectional view illustrating a locking mechanism constructed in accordance with an embodiment of my in-

vention and in applied position; Fig. 2 is a vertical sectional view illustrating a locking mechanism constructed in accordance with another embodiment of my invention; Fig. 3 is a vertical sectional view illustrating a locking mechanism constructed in accordance with a still further embodiment of my invention; Fig. 4 is a vertical sectional view illustrating a locking mechanism constructed in accordance with another embodiment of my invention; Fig. 5 is a vertical sectional view illustrating a locking mechanism constructed in accordance with another modified form of my invention; Fig. 6 is a fragmentary horizontal sectional view taken substantially on the line 6—6 of Fig. 5; and Fig. 7 is a vertical sectional view illustrating a locking mechanism constructed in accordance with a still further modified form of my invention.

As is particularly illustrated in Fig. 1, S denotes the actuator rods or shifting shaft housing and in which operate in a conventional manner the actuator rods or shifting shafts R, the same being arranged, in a well known manner, substantially in parallelism and which are adapted to be separately operated, as is well known, by a shoulder lever. As the means for operating the rods or shafts S forms no particular part of my present invention and being well known, it is not thought that a detailed description and illustration thereof is necessary.

Mounted upon the housing S is a casing C provided in its bottom wall 1 with two spaced openings 2 which register with the threaded openings 3 provided in the adjacent or top wall 4 of the housing S.

Disposed through each pair of registering openings 2 and 3 and engaging the threads of the opening 3 is a bushing 5 provided at its outer end with an outstanding annular flange or head 6 which engages the inner face of the wall 1 of the casing C whereby the bushing 5 serves to maintain the casing C in applied position upon the housing S. The central portion of the outer or top wall 7 of the casing C is provided with a relatively large circular opening 8, having its lower marginal portion defined by an inwardly directed flange 9. The opening 8 is also defined by an outstanding flange 10 of a length required by the occasions of practice.

Snugly fitting within the lower portion of 110

the central opening defined by the flange 10 is a rotatable disk 11 having its lower portion 11^a reduced in diameter to extend within the opening defined by the flange 9 and whereby a shoulder 12 is provided to rest on the flange 9 whereby the disk 11 is maintained against downward displacement and in a manner to permit its unobstructed rotation.

10 At its axial center, the disk 11 is provided with an opening 14, the wall of which being provided with a female spiral groove 15 to receive the spiral thread 16 extending outwardly from the periphery of the cylindrical member 17. The lower or outer end portion of the member 17, at substantially its axial center, is provided with an outstanding lug 18 through which is directed an elongated rod 19 extending beyond opposite sides of the member 17. The rod 19, after applied, is held against longitudinal movement through the instrumentality of the pins 20 disposed therethrough at opposite sides of the lug 18 and substantially in contact therewith.

Disposed through the bushings 5 are the plungers 21 having endwise movement therethrough and which, upon movement in one direction, are adapted to engage within the recesses 22 provided in the rods or shafts R when said rods or shafts are in neutral position. By this means, the rods or shafts R are locked against movement when in neutral position and for the purpose of preventing the use of the vehicle, or the like, by unauthorized persons.

The extremities of the rod 19 engage within the openings 23 provided in the end portions of the plunger 21 within the casing C whereby said plungers 21 can be raised or lowered upon requisite endwise movement of the member 17 upon rotation of the disk 11.

The bushings 5, in a comparatively small space, provide sufficient bearing area for the plungers and also increase the strength of the plungers at their lower or working extremities.

Arranged within the central opening defined by the flange 10 and in threaded engagement with said flange is a bushing or plug 24 which is locked in applied position through the instrumentality of the pin 25 or its equivalent. The inner or inserted face of the bushing or plug 24 is provided at its axial center with a circular recess 26 into which extends a pin 27 projecting from the outer face of the disk 11 to one side of the bore 14 thereof.

60 The bushing 24 serves to prevent the disk 11 from lifting and mounted within said bushing 24 is a key actuated mechanism 28, of any preferred type, including a rotatable member 29 operable under the influence of 65 the key. The rotatable member 29 extends

within the recess 26 and said portion thereof is provided with a bolt or rock arm 30. In Fig. 1 the plungers 21 are shown in locking engagement with the rods or shafts R. For unlocking, the bolt or arm 30 is turned clockwise by means of a key until it engages the pin 27 and the requisite turning motion is continued resulting in the pin 27 and the disk 11 moving with the bolt or arm 30 and during which movement, the member 17 will move upwardly and lift the plungers 21 from within the recesses 22 and thereby free the rods or shafts R for actuation. In practice, it is preferred that the requisite release of the rods or shafts R be accomplished upon substantially one complete revolution of the rotating member 29. For locking, the operation is reverse to that just set forth.

In Fig. 2 of the drawings, the mechanism is substantially the same as that set forth with respect to Fig. 1 except that the casing C' is integral with the housing S' and the plungers 21^a operate directly through the openings 31 suitably provided in the single wall 4^a separating the housing S' and the casing C'. As the remaining portions of the device as disclosed in Fig. 2 are similar to Fig. 1, such parts are identified by the same reference characters.

In the embodiment of my invention illustrated in Fig. 3, the disk 11^a at its axial center is provided with a depending cylindrical member 17^a, having extending outwardly from its periphery a spiral thread 32 which engages within a female spiral groove 33 provided in the internal wall of a sleeve 34. The sleeve 34, at diametrically opposed points, is provided with the outstanding lugs 35 engaged within the openings 36 provided in the adjacent end portions of the plungers 21^b. The plungers 21^b coact with the rods or shafts R in the same manner as has hereinbefore been described with respect to the embodiment of my invention as disclosed in Fig. 1, and the disk 11^a is rotated in the same manner and for which reason a further detailed description is believed to be unnecessary.

As illustrated in Fig. 4 of the accompanying drawings, the housing S^a is provided with a relatively large opening 37 through which is directed a trunnion 38 depending from the lower wall of the casing C^a. The periphery of the trunnion 38 is threaded to properly engage with the nut or reinforcing plate 39 arranged within the housing S^a and having substantially close contact with the adjacent face of said housing. The nut or plate 39 is held against rotation through the instrumentality of the screws 40 or the like disposed through the lower wall of the casing C^a at opposite sides of the trunnion 38, through the adjacent wall of the housing S^a and through the nut or plate 39.

The lower portion of the trunnion 38 or

that portion thereof within the housing S^a is provided at diametrically opposed points in its wall with the slots 41 through which are disposed the opposite end portions of a cross member 42. The end portions of this member 42 engage within the recesses 43 provided in the opposed side faces of the rods or shafts R^a , and which end portions of the cross member 42 engage therein when 10 said shafts or rods R^a are in neutral position.

The central portion of the cross member 42 is threaded or otherwise engaged with the lower end portion of a plunger 44 which 15 is actuated in substantially the same manner as has hereinbefore been set forth with respect to the mechanism embodied in the preceding forms of my invention.

In the form of my invention illustrated 20 in Fig. 5, the cross member 42' is adapted for coaction with the recesses 43' provided in the opposed side faces of the actuator rods or shafts. The member 42' also is engaged, when in a released position with respect to the shafts or rods, within the vertically disposed holding grooves or slots 45 provided within the housing S^b . Threaded through the central portion of the member 42' is the lower end portion of a rod 44'. The 30 upper end portion of the rod 44' is provided with a circular head or disk 46 resting upon a sleeve or bearing 47 anchored within the casing C^b . Extending upwardly from the disk or head 46 is a pin 27^b with which 35 acts the bolt or rock arm 30^b carried by the rotatable member 29^b comprised in the key actuating mechanism and which pin 27^b and the bolt or rock arm 30^b have relative contact or engagement for the same purpose as has hereinbefore been more particularly set forth with respect to the pin 27 and the rock arm or bolt 30. Upon rotation 40 of the rod 44' in one direction, the cross member 42' is raised out of operative engagement within the recesses 43' when the actuator rods or shafts are in neutral.

In the form of invention illustrated in Fig. 7, the rod 44^a is directly carried by the key actuated member 29^a. The lower portion of the rod 44^a is in threaded engagement with the cross member 42^a which coacts in the same manner as has hereinbefore been set forth with the recesses 43^a in the actuator rods or shafts with the exception that the member 42^a is in releasing position when moved downwardly below said rods or shafts and which downward movement is limited by a stop 48 threaded upon the lower end portion of the rod 44^a. The member 48 is held against displacement by a pin 49 inserted through the rod 44^a below the member 48. The member 42^a also extends through the diametrically opposed open end guide slots 50 provided in the

walls of the sleeve or barrel 51 depending 65 from the top wall 52 of the housing S^c and which substantially defines the opening 53 affording communication between the housing S^c and the casing C^c .

From the foregoing description it is 70 thought to be obvious that a mechanism constructed in accordance with my invention is particularly well adapted for use by reason of the convenience and facility with which it may be assembled and operated, 75 and it will also be obvious that my invention is susceptible of some change and modification without departing from the principles and spirit thereof, and for this reason I do not wish to be understood as limiting 80 myself to the precise arrangement and formation of the several parts herein shown in carrying out my invention in practice except as hereinafter claimed.

I claim:—

1. In combination with a fixed member, a shifter device movable relatively thereto and provided with a stop, a plunger carried by the fixed member and held against rotation thereby, said plunger coöperating with the 90 stop of the shifter device for retaining said shifter device in a set position, a rotatable element supported by the fixed member, a member operatively connected with the plunger and moving endwise upon rotation 95 of the rotatable element and key actuating means for rotating the rotatable element.

2. In combination with a fixed member, a shifter device movable relative thereto, a pair of members carried by the fixed member, 100 one of said members being rotatable and the second member being held against rotation but movable toward or from the first member upon requisite rotation of the first member, key actuated means for operating the rotatable member, and a plunger operatively connected with the second member for movement therewith, said plunger, upon movement in one direction, engaging the shifter device for holding the same 105 in a set position.

3. In combination with a fixed member, a shifter device movable relative thereto, two members supported by the fixed member and in threaded engagement one with the other, 115 one of said members being rotatable and imparting movement, upon rotation, to the second member in a direction toward or from the rotatable member, key actuated means for operating the rotatable member, 120 and a plunger operatively connected with the second member and engaging the stop of the shifter device upon movement of the rotatable member in one direction.

4. In combination with a housing, a shifter device movable relative thereto, a casing mounted upon the housing, a bushing securing the casing to the housing, a plun-

ger movable through the bushing and engageable with the shifter device to hold the same in a set position, a rotatable member supported within the casing, means for rotating the same, a member operatively engaged with the plunger and in threaded engagement with the rotatable member, said

last named member and plunger moving endwise upon rotation of the rotatable member to either engage or disengage the shifter device. 10

In testimony whereof I hereunto affix my signature.

YUSKE MIYASAKI,
